FIRE EXTINGUISHER

Scott V. Bower, Warren, Ohio

Application February 21, 1948, Serial No. 9,982

4 Claims. (Cl. 169—32)

1

My invention relates to fire extinguishers, and the principal object of my invention is to provide new and improved fire extinguishers.

The type of fire extinguisher now commercially available has serious disadvantages, recognized not only by users but also by manufacturers. For example, most types of extinguishers now on the market are required to be turned end for end, in order to bring about a mixture of chemicals to produce a fire fighting stream.

It has been found that one person cannot turn the present type extinguisher end for end, and also at the same time properly control direction of the outlet hose. Thus, in this operation, the outlet hose, which is turned at least partially upward, may spray contents of the extinguisher on the user or on some proximate person or object, with damaging results.

Further, the present type of extinguisher has considerable weight, and is awkward to handle, thus requiring that a user possess considerable strength in order to properly turn the extinguisher end for end.

Another serious disadvantage arises when a user must leave the floor or a supporting surface in order to get in proximity to the fire, such for example, when a user may be required to climb a ladder to get close enough to the fire to effectively use the extinguisher. Under such conditions, a user does not ordinarily have both hands free to invert the present type extinguisher, and to free both hands for this purpose may be hazardous.

Many other disadvantages of the present type fire extinguisher may be pointed out, but it is believed that the following description is sufficient to show the many advantages that my invention provides over the prior art.

In the drawing accompanying this specification and forming part of this application, there is shown, for purposes of illustration, an embodiment which my invention may assume, and in this drawing:

Figure 1 is a broken longitudinal sectional view of a fire extinguisher illustrating an embodiment of my invention.

Figure 2 is a broken longitudinal view, partly in section and on a reduced scale, showing position of parts when the extinguisher is in operation.

Figure 3 is an exploded perspective view of certain parts used in the embodiment shown in Figures 1 and 2, and

Figure 4 is an enlarged transverse sectional view corresponding generally to the line 4—4 of Figure 1.

2

Referring to the drawing, the embodiment herein shown to illustrate the invention comprises a casing 10 which may be of a construction now extensively used. As best seen in Figure 2, the casing 10 is generally cylindrical and of greater length than diameter, as is customary although not essential.

The casing has a bottom 11, and at its top terminates in an exteriorly threaded opening 12. A cap 13 is threaded to close the opening 12, a seal 14 preferably being interposed between adjoining surfaces of the cap 13 and opening 12. A hand wheel 15 is integrally secured to the cap 13, for the purpose of threading the cap on or off the threads at the opening 12. The foregoing construction is well known in the art, and is shown and described only to better illustrate my invention.

Referring particularly to Figure 1, a plug 16 is secured centrally of the cap 13, the plug having a lower portion 17 threaded through a central aperture in the cap 13. A cup member 18 is fixedly secured to the inner surface of the cap 13, and comprises a circular skirt 19 and a spanning wall 20. The wall 20 has a central threaded aperture receiving the threaded portion 17, and preferably the terminal end of the portion 17 is peened over to lock the parts together. If desired, machine screws 21 may be threaded through the cap 13 and the spanning wall 20 to further secure the parts against rotation.

An upper portion 22 of the plug 16 is exteriorly threaded to receive a gland nut 23. A shaft 24 extends through aligned apertures in the nut 23 and plug 16, and, as here shown, is integrally formed with a second cup member 25 rotatably fitting within the cup member 18. The cup member 25 comprises a circular skirt 26, and a spanning wall 27 from which the shaft 24 extends. Projecting from a terminal margin of the skirt 26 is a pair of diametrically opposed lugs 28, for a purpose to be later described.

As best seen in Figure 3, the skirt 19 of the cup member 18 is formed with a plurality of bayonet slots 29, here shown to be four in number. Each bayonet slot 29 comprises an entrance portion 30 and a retainer portion 31.

Cooperable with the bayonet slots 29 are four projections 32 formed on a receptacle holder 33. The projections 32 are here shown as extensions of a flange 34 formed integral with a cage 35 which terminates in a circular band 36. The flange 34 is formed with diametrically opposed slots 37 for receiving the lugs 28 on the cup member 25.

A receptacle 38 is carried by the holder 33, and

as here shown comprises a glass bottle having a body portion 39, and a mouth portion 40. The mouth portion is provided with an annular bead, so that machine screws 41 threaded through the band 36 of the holder 33 will secure the receptacle in assembled position with the holder 33.

A stopper may be used to close the opening into the mouth portion, and since the receptacle 38 usually contains an acid, the stopper is preferably made of lead. The stopper, as here shown, comprises a cap portion 42 and a stem portion 43 loosely fitting into the opening of the bottle. In the embodiment disclosed, a wire 44 spans the flange to prevent the stopper from being disassembled with respect to the receptacle 38, but to permit free movement of the stopper in a direction to uncover the opening into the mouth portion 40.

When the fire extinguisher herein disclosed is in condition ready for use, the lugs 32 of the receptacle holder 33 are seated within the retainer portions 31 of respective bayonet slots 29, thus releasably supporting the receptacle holder 33 and the receptacle 38 in position spaced from the bottom 11 of the casing 10.

Connection of the receptacle holder may be readily effected by inserting the lugs 32 into the entrance portions 30 of the bayonet slots 29, after first lining up the slots 31 in the holder 33 with the tongues 28 on the cup member 25, and then rotating the holder 33 to seat the lugs 32 in the retainer portions 31 of the bayonet slots 29. It will be clear that the cup member 25 will rotate with the holder 33, by reason of the tongue and groove connection 28, 37.

With the parts as just described, the receptacle holder 33 and receptacle 38 may be released from the cup member 18 by proper rotation of the shaft 24 of the cup member 25. A hand wheel 44 is secured to the exterior portion of the shaft 24 to enable a user to conveniently rotate the cup member 25.

Rotation of the cup member 25 in the proper direction will cause simultaneous rotation of the holder 33, rotation continuing until the lugs 32 on the holder 33 vertically align with the entrance portions 30 of the bayonet slots 29, whereupon the holder 33 may be disengaged from the cup member 18. The weight of the holder 33, together with the weight of the receptacle 38 is sufficient to cause this assembly to drop out of engagement with the cup member 18.

Normally the casing 10 is substantially filled with a fluid, and the receptacle 38 is preferably only partially filled with a substance, such as a liquid, which is mixable with the fluid in the casing 10 to provide the fire extinguishing charge. This charge produces a pressure condition within the casing 10, so that the charge is expelled from the casing through a tube 45 extending upwardly from the bottom 11 and connected to the usual exterior hose 46.

When the holder 33 and receptacle 38 are released from engagement with the cup member 18, the receptacle and holder drop into the liquid in the casing 10. The holder 33 is of sufficient weight so that it and the receptacle will sink in the liquid in the casing, and since the receptacle 38 is only partly filled, it will provide a buoyant portion spaced from the holder 33, so that the receptacle will invert itself in the distance it travels toward the bottom 11, and will be generally completely inverted when it reaches the bottom, as shown in Figure 2.

Inversion of the receptacle 38 causes the

stopper 42 to drop of its own weight to uncover the opening into the mouth portion 40 of the receptacle 38, so that the contents of the receptacle will contact with the fluid in the casing to provide the fire extinguisher charge which will be expelled through the tube 45 and the hose 46. Thus, it will be seen that the extinguishing charge may be generated without turning the casing end for end, and therefore the disadvantages of the prior art are avoided. Further, the substance in the receptacle 38 is brought into contact with the fluid in the casing 10 at the lowermost portion of the casing, so as to provide for good mixing action of the substances producing the fire extinguishing charge.

From the foregoing, it will be apparent to those skilled in the art that I have accomplished at least the principal object of my invention, and it also will be apparent to those skilled in the art that the embodiment herein described may be variously changed and modified, without departing from the spirit of the invention, and that the invention is capable of uses and has advantages not herein specifically described; hence it will be appreciated that the herein disclosed embodiment is illustrative only, and that my invention is not limited thereto.

I claim:

1. A fire extinguisher, comprising: a generally upright casing; a liquid in said casing; a receptacle releasably supported in upright relation from an upper portion of said casing, said receptacle containing a substance mixable with said liquid; means for releasing said receptacle so that it is free to drop into and sink in said fluid; and weight means adjacent to the opening in said receptacle for overbalancing and inverting said receptacle as it sinks in said fluid.

2. A fire extinguisher, comprising: a generally upright casing; a liquid in said casing; a receptacle releasably supported in upright relation from an upper portion of said casing, said receptacle containing a substance mixable with said liquid; means for releasing said receptacle from its support on said casing so that said receptacle is free to drop into and sink said fluid; weight means adjacent to the opening in said receptacle for overbalancing and inverting said receptacle as it sinks in said fluid; and buoyancy producing means combining with said weight means holding said receptacle in inverted relation.

3. A fire extinguisher, comprising: a generally upright casing; a liquid in said casing; a receptacle releasably supported in upright relation from an upper portion of said casing; a substance in said receptacle which is mixable with said liquid to produce a fire-fighting product, said substance occupying only a portion of the capacity of said receptacle so that a space remains in said receptacle, and being shiftable longitudinally of said receptacle; means for releasing said receptacle from its support on said casing so that said receptacle is free to drop into and sink in said fluid; weight means adjacent to the opening in said receptacle for overbalancing and inverting said receptacle when it sinks in said fluid; said substance shifting toward the opening of said receptacle when the latter is inverted to provide a buoyant portion spaced from said weight means and combining therewith to hold said receptacle in inverted relation.

4. A fire extinguisher, comprising: a generally upright casing; a first liquid in said casing; a receptacle releasably supported in upright relation

from an upper portion of said casing; a second liquid in said receptacle which is mixable with said first liquid to produce a fire-fighting product, said second liquid occupying only a portion of the capacity of said receptacle so that a space remains in said receptacle; means for releasing said receptacle from its support on said casing so that said receptacle is free to drop into and sink in said first fluid; weight means adjacent to the opening in said receptacle, comprising a cover closing the opening into said receptacle and being movable to position uncovering said opening by gravitational force when said receptacle is inverted, said weight means being operable to overbalance and invert said receptacle when it sinks in said first fluid; said second liquid gravitating toward the opening of said receptacle when the latter is inverted to provide a buoyant portion spaced from said weight

means and combining therewith to hold said receptacle in inverted relation.
